UNITED STATES PATENT OFFICE.

RICHARD F. AMERICA, OF PHILADELPHIA, PENNSYLVANIA.

DESIGN FOR A TIRE.

51,193.

Specification for Design. Patented Aug. 28, 1917.

Application filed May 23, 1917. Serial No. 170,554. Term of patent 14 years.

To all whom it may concern:

Be it known that I, RICHARD F. AMERICA, a citizen of the United States, and a resident of Philadelphia, in the county of Philadelphia and State of Pennsylvania, United States of America, have invented a new, original, and ornamental Design for a Tire, of which the following is a specification, reference being had to the accompanying drawing, forming part thereof.

Figure 1 is a face view of a section of a tire embodying my new design;

Fig. 2 is a cross section on the line 2—2, Fig. 1; and

Fig. 3 is a cross section on the line 3—3, Fig. 1.

I claim:

The ornamental design for a tire, as shown.

RICHARD F. AMERICA.
